UNITED STATES PATENT OFFICE.

GEORGE H. CONDE, OF ALBANY, NEW YORK, ASSIGNOR OF ONE-HALF TO
WILLIAM McGEOCH, OF SAME PLACE.

METALLIC HAT-STRETCHER.

SPECIFICATION forming part of Letters Patent No. 424,094, dated March 25, 1890.

Application filed December 28, 1889. Serial No. 334,346. (No model.)

To all whom it may concern:

Be it known that I, GEORGE H. CONDE, a citizen of the United States, residing at the city and county of Albany, State of New York, have invented a new and useful Metallic Hat-Stretcher, of which the following is a specification.

My invention relates to improvements in devices for stretching hats; and the object of 10 my invention is to provide a hat-stretcher to which heat may be applied for the purpose of increasing the size of the hat, causing it to retain its enlarged form without breaking or wrinkling the fabric of which the hat is composed. I attain these objects by the mechanism illustrated in the accompanying drawings, in which—

Figure 1 is an elevation; Fig. 2, a plan; Fig. 3, a section along the lines 1 1 on Fig. 2; Fig. 20 4, a section along the lines 2 2 on Fig. 2; and Fig. 5 shows the stretcher placed in a receptacle to which heat is applied.

Similar letters refer to similar parts throughout the several views.

For the purpose of increasing the size of a 25 hat it has been customary to place a wooden block into the hat and operate a screw provided with a right and left hand thread meshing with threads on screws attached to 30 opposite sections of said block, and in this manner causing the sections of the block to be forced apart, the elasticity of the material of which the hat is composed allowing the hat to be thus enlarged. The objection to this 35 mode of stretching the hat is that after the block has been removed the hat will retain the form given to it but a short time, and will then resume the position which it occupied prior to the stretching process. Another 40 objection to the use of the block referred to is that by attempting to stretch it beyond a certain limited degree the hat is broken. The hat also becomes wrinkled or uneven after the removal of the block, caused by the elastic material attempting to resume its normal 45 position. All of these difficulties are surmounted in the process of stretching a hat by the use of my invention.

In the manufacture of stiff hats there is a 50 large amount of shellac used. By applying heat to the hat in connection with pressure

the shellac becomes softened, allowing the material to be forced to the position desired, and after the removal of the pressure and heat the shellac will harden again and hold 55 the material in the position which it attains by the use of the stretcher.

A represents a narrow thin metallic frame, oval in form, composed of any suitable metal, and divided transversely into two sections, 60 each of which sections is provided near a point midway between the ends of the section with the screw S, the one provided with a right-hand and the other with a left-hand thread. The handle H is provided with a female 65 thread at each end, one meshing with the right-hand and the other with the left-hand thread of the screws S S. The handle H is provided with a series of slots O, extending through from one side to the other side of the 70 handle.

For the purpose of applying heat to my hat-stretcher, I place the same in the receptacle R, usually constructed of tin and provided with the cover T, which I place over an alcohol-lamp, as shown in Fig. 5, or in contact with any other source of heat that may be desired. When the stretcher has been subjected to a sufficient amount of heat, I place the same in the hat, operate the handle H 75 until the hat has been increased in size to the extent desired, and then remove the same, and the hat will retain the position given it by the use of the stretcher without being in any way injured, either by breaking or unevenness of surface. In this manner a hat 80 can be enlarged twice as much as could be done by the wooden stretcher now in use, and it will retain its enlarged form after the removal of the stretcher, which it would not do 85 if the wooden stretcher were employed.

I do not limit myself to the use of the receptacle R, in which to place my stretcher, the sole object being to apply heat to the stretcher, which may be done in many different ways.

The object of providing the handle with slots or openings is that it will not become so hot when placed in the heating-receptacle that it cannot be comfortably used.

My invention is simple in its construction and operation, inexpensive, and performs the 100

work required of it in an extremely satisfactory and positive manner.

I am aware that Letters Patent of the United States No. 157,845, dated December 5 15, 1874, for combined hat measurers and stretchers show a wooden block divided into two sections operated by a screw and has metallic strips situated on each side of the upper edge of the segments, and I therefore do not claim that construction.

What I claim as my invention, and desire to secure by Letters Patent, is—

In a hat-stretcher, the combination of a me-

tallic frame composed of two sections, each provided on its concave side, about midway between its ends, with a lug rigidly attached thereto, said lugs provided the one with a right-hand and the other with a left-hand screw-thread, with a handle II, provided at each end with a female screw-thread meshing, respectively, with the threads on said lugs, all substantially as described.

GEO. H. CONDE.
